SOUNDING DEVICE

John A. Jowett, Scottsville, N. Y.

Application August 11, 1943, Serial No. 498,437

2 Claims. (Cl. 116—149)

1

My invention relates to a sounding device or bell, particularly a sounding device adapted for use at dinners or meetings, for example, for calling the meeting to order.

An object of my invention is to provide a sounding device or bell of simple construction which is more convenient to use.

Another object of my invention is to provide a bell structure which is equipped with a hand actuated striker within easy reach of the user.

My invention further contemplates the provision of a bell in which means is provided to cut off the vibration or sounding of the bell, if desired.

Other objects and advantages of my invention will be set forth in the claims and will be apparent from the following description, when taken in connection with the accompanying drawing, in which:

Fig. 1 is a view, partially in section, showing the sounding device or bell construction of my invention;

Fig. 2 is a view taken substantially on the line 2—2 of Fig. 1;

Fig. 3 is a view similar to that of Fig. 1 with the bell in a closer adjusted position with respect to the base or support.

It is the usual practice at meetings of various kinds to provide the president or the person who conducts the meeting with a bell or other sounding device which is normally struck by a gavel or wooden hammer for the purpose of sounding the bell. Quite frequently the gavel is misplaced or not within convenient reach of the user so as to cause delays when it is desired to call the meeting to order or to restore order.

The sounding device or bell of my invention preferably comprises a bell 11 of metal or any suitable material. While I have shown a bell it will, of course, be appreciated that other shapes of sounding devices may be used. The bell has a rod 12 upon which it is supported, the upper end of the rod 12 being threaded and extending through the top of the bell for the reception of a nut 13 which may be ornamental, if desired.

The lower end of the rod 12 is threaded, as shown at 14, and is adapted to extend through an opening 15 provided in a base or support 17. The base may be of any suitable shape and may be of wood or other desired material. Threaded on the rod is a pair of nut and washer assemblies 18 and 19 which when tightened against the base, clamp the base between them so as to support the bell rigidly in an upright position.

Carried on the rod 12 is a bumper 21 of rubber

or any other suitable material against which a striker or hammer 22 is adapted to normally rest. The striker 22 may be of metal and may be connected by a rod 23 to a lever 24 which extends outward beneath the lip 26 of the bell, as shown in the drawing. If desired the parts 22, 23 and 24 may be a single piece construction with the outwardly projecting end 27 constituting a finger piece for actuating the striker.

10 Mounted on the base or support 17 is a bracket 28 which has a pair of arms 29 through which a pin 31 extends. The pin also extends through the lever 24 and constitutes a pivot for the lever. Normally the striker assembly is weighted so that it will freely swing about the pivot with the striker 22 in engagement with the bumper 21. However, I preferably provide the striker assembly with a spring 32, one end of which engages an element 34 provided on the lever 24 and the other end of which bears against the base. The intermediate portions of the spring are coiled about the pin 31, as shown most clearly in Fig. 2, so that the spring will urge the striker assembly into the position shown in Fig. 1.

15 Normally the parts are in the position shown in Fig. 1 and when the user desires to call a meeting to order he merely presses on the finger piece 27 as many times as desired until order is obtained. It will be appreciated that the bell 20 when struck will resound and continue to vibrate perhaps long after it is desired that the bell should cease to resound. Quite frequently the user of a bell with an ordinary gavel sounds the bell and then places his hand on the bell in order to prevent it from continuing to resound. 25 With my bell I have provided novel means for doing this automatically when desired.

20 To accomplish this the clamping nut 18 is loosened and threaded upward on the rod and the clamping nut 19 shifted upward to engage the bottom of the base or support. With the parts in this adjusted position as shown in Fig. 3 the bell is moved closer to the base so that the lower lip 26 of the bell is engaged by the top surface 35 of the lever 27 when the parts are in their normal position as shown in Fig. 3.

25 The spring serves to press the lever tightly against the lip of the bell so as to cause the bell to cease to vibrate. In practice, the user presses downward on the lever 27 which causes the bell to be struck. He thereupon releases the finger piece 27 and the spring returns the parts to the position shown in Fig. 3, with the lever tightly pressed into engagement with the lip of the bell. 30 Thus the bell is sounded once and immediately

the vibration or continued sounding of the bell is cut off. Of course, the user may strike the bell any desired number of times.

While I have shown and described the preferred form of my invention, it will be appreciated that various changes and modifications may be made therein, particularly in the form and relation of parts, without departing from the spirit of my invention as set forth in the appended claims.

I claim:

1. A device of the character described comprising, in combination, a base, a bell having a lower lip, an element for supporting the bell from the base, a lever having a fulcrum on the base and having a manually actuated end extending beneath the lip, a striker attached to the opposite end of the lever, a spring normally urging said striker out of engagement with the bell, said bell being shiftable toward and from the base so that

when shifted toward the base the manually actuated end of the lever will engage the lip of the bell under the influence of said spring to cut off the sounding of the bell after being struck.

2. A device of the character described comprising, in combination, a base, a bell having a lower lip, an element for supporting the bell from the base, a lever having a fulcrum on the base and having a manually actuated end extending beneath the lip, a striker attached to the other end of the lever, a spring normally urging said striker out of engagement with the bell, and means enabling the bell and said manually actuated end to be shifted with respect to each other so that said manually actuated end will engage the lip under the influence of said spring when desired to cut off sounding of the bell after being struck.

JOHN A. JOWETT.
